F. H. BURGHER.
SUCTION SWEEPER.
APPLICATION FILED DEC. 31, 1917.

1,404,699.

Patented Jan. 24, 1922.

UNITED STATES PATENT OFFICE.

FRED H. BURGHER, OF LAKEWOOD, OHIO, ASSIGNOR TO THE MARVEL COMPANY, OF CLEVELAND, OHIO, A CORPORATION OF OHIO.

SUCTION SWEEPER.

1,404,699.

Specification of Letters Patent. Patented Jan. 24, 1922.

Application filed December 31, 1917. Serial No. 209,766.

To all whom it may concern:

Be it known that I, FRED H. BURGHER, a citizen of the United States, and a resident of Lakewood, county of Cuyahoga, and State of Ohio, have invented a new and useful Improvement in Suction Sweepers, of which the following is a specification, the principle of the invention being herein explained and the best mode in which I have 10 contemplated applying that principle, so as to distinguish it from other inventions.

The present invention relates as shown to suction sweepers and more particularly to that type of suction sweeper in which the 15 rotation of the suction fan is obtained by the traction of the sweeper across the floor, power being transmitted from the wheels to the fan by means of a simple arrangement of gears. I have also provided means between the fan and the driving wheels whereby the fan is continuously driven on both 20 the forward and backward movement of the sweeper, and also means whereby the fan is disengaged from the driving means and is free to continue its rotation when the movement of the sweeper is arrested.

I have provided a simple and efficient means for adjusting the height of the nozzle of the sweeper from the surface of the 30 floor, and have constructed a machine which is very low in height thereby adapting it to use under furniture and other articles which is not accomplished by most other machines of this sort, the total height of the machine 35 being about five inches.

To the accomplishment of the foregoing and related ends, said invention, then, consists of the means hereinafter fully described and particularly pointed out in the 40 claims.

The annexed drawing and the following description set forth in detail certain mechanism embodying the invention, such disclosed means constituting, however, but one 45 of various mechanical forms in which the principle of the invention may be used.

In said annexed drawing:—

Fig. 1 is a vertical longitudinal section through my suction sweeper showing part 50 of the driving means in section. Fig. 2 is a section at right angles to Fig. 1 as shown by line 2—2 on Fig. 1, Fig. 3 is a bottom plan view of my suction sweeper; Fig. 4 is

a perspective view of the supporting bracket of the height adjusting roller; and Fig. 5 is 55 a section through the clutch mechanism.

I have shown a suction sweeper in which is provided a lower member or housing 1 which terminates at its outer end in a nozzle 2 and is provided with a substantially 60 horizontal surface 3 on its upper face.

Disposed at right angles to the surface 3 is a shaft 4 on which is fastened the suction fan 5. Ball bearings 6 for the shaft 5 are provided in the housing 1. A casing 7 is 65 securely fastened to the housing and so disposed above the surface 3 that it forms a suction chamber for the fan 5. This casing 7 terminates at the end opposite to the nozzle 2 in an outlet 8 to which is attached a 70 dust bag or retainer which is not shown. An aperture 9 is provided in the housing 1 thereby providing an outlet from the nozzle 2 to the fan chamber.

I have provided a simple and efficient 75 means for transmitting rotary movement from the wheels 12, which are provided with friction surfaces 13, to the fan 5 which consists of a pinion 14 mounted on the shaft 4 and engaging a gear 15 rotatably mounted 80 on a stud 16 in the housing 1. Integral therewith or otherwise fastened to the gear 15 is a bevel pinion 17 adapted to engage two bevel gears 18 which are rotatably mounted on the shaft 10, which is carried in 85 extensions 11 of the casing or housing 1. Fastened to the shaft 10 and adjacent the bevel gears 18 and in driving connection therewith are one way clutches 19 so disposed as to operate in opposite directions, 90 one of the clutches operating as the sweeper is moved in a forward direction and the other operating when the sweeper is drawn backward. By means of this construction the fan is continuously driven regardless of 95 the movement in either direction of the sweeper, and the fan will continue to rotate after movement of the sweeper is arrested since the clutches operate only on rotation of the shaft 10.

100 Downwardly depending walls 20, are provided on the housing 1 forming a chamber 21 which is adapted to enclose the fan driving mechanism and has a cover 22 retained by screws or other means thereto.

105 Disposed adjacent the driving wheels 12

- and having bearings on the shaft 10 is a yoke 23 to which is secured the operating handle 24. By connecting the yoke in this manner to the shaft 10 all the thrust is taken about the axis of the shaft and there is no tendency of the sweeper to upset or to raise the nozzle of the machine away from the floor when the direction of movement is reversed.
- 10 Cast integral therewith and to the rear of the opening 25 of the nozzle 2 in the housing 1 is a chamber or recess 26 in which a roller 27 is adapted to fit. A forked frame or member 28 of spring metal is provided which is adapted to act as a bearing for the shaft 29 on which the roller 27 is fitted.
- 15 The frame 28 is provided at its outer ends with projections 30 bent at right angles which are adapted to be sprung into apertures 31 in the side walls of the chamber 26. The opposite end of the member 28 terminates in a loop or bearing 32 which is engaged by the shank of a thumb screw 33 which engages a threaded recess in the housing 1. A belt 34 engages the roller 27 and forms a driving connection between the roller 27 and a brush 35 which is rotatably retained in the nozzle 2.
- 20 By this construction it will be seen that a simple means has been provided for adjusting the height of the nozzle from the floor and by enclosing the recess 26 in the housing 1, I do not permit any leakage of suction to occur about the roller 27.
- 25 As will be seen by the foregoing description and drawing I have constructed a suction sweeper which is simple in construction, of few parts and very low in height so as to adapt it to use in cleaning under low articles of furniture.
- 30 Other modes of applying the principle of my invention may be employed instead of the one explained, change being made as regards the mechanism herein disclosed, provided the means stated by any of the follow-

ing claims or the equivalent of such stated means be employed.

I therefore particularly point out and distinctly claim as my invention:—

1. In a device of the character described 50 the combination of a horizontal fan casing formed with an outlet passageway at one side thereof, a suction chamber and a transmission housing below said casing, a partition wall separating said suction chamber 55 and transmission housing, lugs formed integrally with said partition wall and projecting horizontally into said transmission housing, a vertical fan shaft journaled in said lugs, a live axle passing horizontally 60 through said transmission housing; reversely operating clutches associated with said axle, driving connections between said clutches and said fan shaft, and a projecting nozzle formed on one side of said suction chamber 65 and an outlet formed on the other side of said suction chamber adjacent said partition and fan shaft.
2. In a device of the character described, 70 the combination of a flat horizontal fan casing of large diameter formed with an outlet passageway on one side thereof, a fan shaft mounted beneath said casing and projecting axially therein, a flat suction chamber, provided at one side with a projecting 75 nozzle, positioned beneath said casing to one side of said fan shaft, an outlet passageway connecting said chamber with said casing at a point adjacent said fan shaft, a transmission housing positioned beneath said 80 casing to the other side of said fan shaft, downwardly projecting extensions on said casing, a live axle extending horizontally through said transmission housing and journaled in the sides thereof and in said 85 downward extensions and driving means connecting said live axle with said fan shaft.

Signed by me, this 27th day of December, 1917.

F. H. BURGHER.
